United States Patent Office

Des. 211,015
Patented May 14, 1968

211,015

CAMPER

Leo M. Hopkins, 1305 W. 10th Ave.,
Milan, Ill. 61264

Filed Oct. 5, 1967, Ser. No. 8,873

Term of patent 14 years

(Cl. D14—3)

Fig. 2.

Fig. 3.

Fig. 4.

Fig. 5.

The broken line illustration of the pick-up truck in FIGURE 1 is for purposes of illustration only.

I claim:

The ornamental design for a camper, as shown and described.
